FOUNDATION GARMENT

Anna Bayer, North Haven, Conn., assignor to The
Strouse, Adler Company, New Haven, Conn., a
corporation of Connecticut

Application July 10, 1948, Serial No. 38,022

2 Claims. (Cl. 2—43)

1

This invention relates to foundation garments of the kind which have two leg portions to encircle the upper parts of the two legs of the wearer. Frequently garments of this kind are referred to as panty type foundation garments. By the term "foundation garment," it will be understood of course that I refer to figure-confining garments, e. g. corsets, girdles, and in general all garments designed to confine and shape the figure. More particularly the invention relates to panty type foundation garments having removable crotch-pieces.

The invention provides a removable crotch-piece, panty type foundation garment which not only is effective in confining the figure, but also is comfortable and substantially free of any tendency to show through any outer garments that may be worn over it.

Speaking generally, in a garment of the invention the leg portions are disconnected from each other at the crotch, and a separate piece is provided, releasably fastened to the front and rear walls of the garment, to close the crotch opening left between the leg parts of the garment; preferably this crotch-piece is sufficiently wide to extend sidewise into both leg portions of the garment, and it is fastened to the garment through tabs to which it is releasably attached and which tabs themselves are permanently attached to the front and rear walls of the garment and present substantially straight edges to corresponding straight edges of the crotch-piece.

The accompanying drawings illustrate a preferred form of my invention as applied to a panty girdle. Fig. 1 is a front view of the girdle, partly broken away to show the crotch-piece in place. Fig. 2 is a front view of the lower portion of the garment without the crotch-piece, broken away to show one of the tabs provided for attachment of the crotch-piece. Fig. 3 is a vertical section on the line III—III of Fig. 1. Fig. 4 shows the crotch-piece, drawn to a larger scale. Fig. 5 shows one of the crotch tabs, also drawn on an enlarged scale.

The garment of the drawing comprises principally four panels $1a$, $1b$, $1c$ and $1d$ which are sewed to one another along longitudinal seams 2 to form a garment which fits snugly about the body from the waistband 3 to the leg portions 4 . The latter are to encircle the tops of the wearer's legs. The side panels $1b$ and $1d$ may be formed of resilient materials; for example, they may have circumferential stretch as indicated by the arrows 5 . Likewise the front and back panels $1a$ and $1c$ may be resilient if desired; for ex-

ample stretchable vertically as indicated by the arrows $5a$. Also the front panel may be provided at its upper end with short stays 6 if desired. A slide fastener 7 at the upper end of one of the seams 2 permits the garment to be put on and taken off easily. The lower ends of the front and back body panels may be cut away to form upwardly extending peaked, or arched, crotch openings as it were (Figs. 1 and 2), and together with the side panels continue into and thus form parts of the leg portions 4 as it were (Figs. 1, 2 and 3). Additional panels 8 then may be sewn at 9 and 10 to the generally arcuate edges of the lower end of the front and back panels to complete the leg portions of the garment and the encirclement of the upper parts of the wearer's legs individually. Usually the two panels 8 are made rather long (i. e. in the vertical direction) so that the leg portions of the garment may have a firm grip on the legs as it were, to resist upward movement of the garment, as will be seen from the drawing. However at their upper edges 11 , two leg panels 8 terminate short of each other, thus leaving the garment open directly at the crotch.

The foregoing illustrates the type of garment to which I regard my invention as particularly applicable, but my invention is not limited either to this form of panel garment, or to garments made of separate panels. Speaking generally it is applicable to any form of open-crotch panty type of foundation garment.

In use the crotch opening is closed, Figs. 1 and 3, by a crotch-piece 12 removably attached to the garment by loosely dependent tabs permanently attached to the front and rear walls of the garment; that is, tabs attached at one end to the garment body and having their other ends swinging free. The crotch-piece is attached to these free ends. Preferably a single tab 13 is used at the front of the garment and another at the back, each being secured to the garment substantially transversely of the garment, Fig. 2, the back tab being attached at a point substantially as high as the top of the leg portions. They may be quite or substantially alike. The free end of each tab 13 , i. e. the end to which the crotch-piece is fastened, has a straight edge as shown at 14 , Fig. 5. The opposite ends 15 of the tabs may be and usually are sewn to the garment body, and are attached near the edges of the peaks of the front and back crotch openings, Fig. 2 and 3, and in such a manner that all parts of the end edge 14 of each tab, if the tab should be permitted to hang downwardly free and unimpeded

from its attachment to the garment, would be at substantially the same distance from the ground, as indicated in Fig. 2; i. e. each lower or free end edge 14 would lie in a substantially horizontal line, Fig. 2, which may either be straight or be curved somewhat due to vertical folds in the tab arising from the shaping of the body portion of the garment. To this end the tabs may be attached to the garment body by the same stitchings as attach the leg panels 8 to the body part of the garment and extensions of these stitchings above the panel edges 11 and the edges of these latter ends 15 of the tabs are curved somewhat, convexly, as indicated at 15, Fig. 5, the straight edge 14 of the free end of each tab being parallel to the chord of the arc of the convex opposite end 15 as shown in Fig. 5, so that in use the tabs also will lie somewhat more smoothly than otherwise as indicated in Fig. 3. Preferably the tabs are made of a resilient material stretchable lengthwise, i. e. in the directions indicated by the arrow 16, Fig. 5; for example, they may be made of a fabric composed of strands of elastic rubber (natural or synthetic) and textile yarns interwoven or knitted with the rubber in a common manner. The tabs are made sufficiently wide (dimension indicated generally by 17, Fig. 5) to lap inside both panels 8 of the leg portions when the garment is in use, Figs. 1 and 3.

The crotch-piece 12 may be, and preferably is, rectangular in shape as shown in Fig. 4. Customarily it is made of a soft, easily laundered material. Its width (dimension 18, Fig. 4) is preferably sufficient to not only span the space between the edges 14 of the leg portions of the garment when in use, but also extends well down into both leg portions, Figs. 1 and 3. This width and the widths of the free ends of the tabs (i. e. the lengths of the edges 14, Fig. 5) may be equal. The length of the crotch-piece (dimension 18a, Fig. 4) is sufficient to permit the crotch-piece to extend from one tab to the other without discomfort to the wearer, and usually somewhat loosely.

The two ends of the crotch-piece, and likewise the free ends of the tabs, at which the complementary releasable fastener elements are provided (buttons, button-holes, snap fasteners, etc.), may be folded or otherwise reinforced as indicated at 19. The sewing at 20 in Fig. 5 is merely stitching of folded edges of the tabs for finish. Preferably the crotch-piece is fastened to the tabs at the inner surfaces of the tabs (i. e. between the tabs and the wearer's body), Fig. 3, and snap fasteners 21 and 21a are used to readily attach the crotch-piece to the tabs. Usually I place at least one fastener element 21a so far along toward each side of each tab, Fig. 5, that each tab has at least one fastener element within each leg portion of the garment, Fig. 3. The crotch-piece having fastener elements 21a cooperating with these particular fastener elements of the tabs, this arrangement tends to hold the two sides of the crotch-piece within the two leg portions.

It will be understood that my invention is not limited to the details of construction and operation described above except as appears hereafter in the claims.

5 I claim:

1. A panty-type foundation garment having a body portion, individual leg portions connected to said body portion to encircle the legs of the wearer, the leg portions being separate from each other directly at the crotch to leave the crotch open, a tab secured to the front and transversely of the garment and having a free dependent end extending toward both leg portions, a tab secured to the back and substantially transversely of the garment at a point substantially as high as the top of the leg portions and having a free dependent end extending toward both leg portions and the edge by which at least one of said tabs is secured to the body portion of the garment being convex and the opposite edge of said tab being straight and parallel to the chord of said convex edge, and a crotch-piece of greater width than the crotch opening and extending into both leg portions, the ends of the crotch-piece and said dependent ends of the tabs having cooperating releasable fastening elements.

2. A panty-type foundation garment having a body portion, said body portion having at its lower edge, an upwardly extending arched crotch opening at the front of the garment and an upwardly extending crotch opening at the back of the garment, individual leg portions connected to said body portion to encircle the legs of the wearer, a tab secured to the front and another tab secured to the back of the garment, said tabs being secured to said body portion adjacent the tops of the crotch-openings, and said tabs having releasable fastener elements, and a crotch-piece having ends provided with releasable fastener elements for releasably fastening the crotch piece to said tabs, and the edge of the front tab by which the said front tab is secured to said body portion of the garment being convex and the opposite edge of the said tab being straight and parallel to the chord of the convex edge.

ANNA BAYER.
